UNITED STATES PATENT OFFICE.

STILLMAN W. ROBINSON, OF COLUMBUS, OHIO.

MACHINE FOR MAKING SCREW-WIRE FOR PEGS.

SPECIFICATION forming part of Letters Patent No. 325,275, dated September 1, 1885.

Application filed October 13, 1884. (No model.)

To all whom it may concern:

Be it known that I, STILLMAN W. ROBINSON, of Columbus, county of Franklin, State of Ohio, have invented an Improvement in 5 Machines for Nicking and Threading Wire, of which the following description, in connection with the accompanying drawings, is a specification, like letters on the drawings representing like parts.

10 So far as my knowledge extends, in all machines heretofore constructed for screw-threading wire the wire to be threaded has been supported by feed-rolls, and in some instances by gripping-rolls in connection with the feed-rolls located only in front of the thread-cutting mechanism, and the wire has remained unsupported between the screw-threading and winding reel or bobbins. Such threading-machines often impart a permanent twist to the 15 wire, and no means being provided back of the cutter to bind or clamp the wire and prevent such torsional twist, or to remove it by giving a counter-torsional twist to the wire to neutralize the first twist given thereto, the 20 said wire leaves the machine or is coiled on the bobbin permanently twisted. This permanent twist is found to be very objectionable when the wire is being uncoiled and used in certain machines for uniting the soles and uppers of boots and shoes.

25 In some wire-cutting machines of the class referred to the wire, after leaving the thread-cutting mechanism, passes through the bore of a comparatively long spindle or rotating hollow shaft which carries the thread-cutter, and which prevents the possibility of binding or clamping the threaded wires sufficiently near to the thread-cutter to overcome the objectionable permanent twist of the threaded 30 wire.

35 My invention has for its object to overcome this objection and to provide a machine in which the wire to be threaded is clamped or gripped immediately in front and in the rear 40 of the die-carrier and die as it is fed through said die and threaded. I accomplish this result by supporting the die-carrier on a comparatively thin rotating pulley or disk, which I provide at its center with any suitable die-carrier and thread-cutting die or dies, and 45 immediately in front of such rotating pulley I arrange feed-rolls, and at the rear of the

said pulley I arrange a second pair of rolls, denominated "pressure-rolls," which, if desired, may also serve as drawing or pulling 55 rolls, the latter rolls being placed as close to the said pulley as the desired thinness of the pulley enabling the said pairs of rolls to be brought so close to the dies as to prevent permanent twist of the wire. The speed of rotation of the feed-rolls and of the pulley and dies is such with relation the one to the other as to impart the desired pitch to the notches or threads cut upon the wire, and the feed-rolls are provided with mechanism to enable 60 the wire placed between them to be gripped with greater or less pressure, as desired.

The invention is fully disclosed in the following specification, and is particularly pointed out in the claims.

70 Figure 1 shows in side elevation, partly in section, a machine for nicking or threading wire embodying my invention. Fig. 2 is a plan thereof; Fig. 3, a sectional view of a piece of flattened nicked or threaded wire of 75 a form shown and described in Letters Patent No. 265,149, granted to me September 26, 1882, that being the class of wire which my machine is especially adapted to prepare. Fig. 4 are details, in end view and section, of 80 the die-carrier and dies employed in my improved screw-thread-cutting mechanism. Fig. 5 shows one of the dies in plan and in end view.

85 The bed-plate A of the machine has erected upon it three standards, B, L, and N, the standard L, carrying the feed-rolls E, being firmly attached to the bed-plate, while the standard B, supporting the pulley or disk C and die-carrier C', and the standard N, having 90 the press-rolls F, are provided with slotted feet 2, through which pass screws h g, which enter the bed-plate and adjustably hold the standards, so as to permit their longitudinal movement on the said bed-plate, and thereby 95 enable the feed and press rolls to be adjusted with relation to the die-carrier and dies to give access to the die-carrier to adjust or remove the die.

100 To enable the feed-rolls E and press-rolls F to be placed in close proximity to the die-carrier C, the latter is mounted in a thin pulley or disk, C², having an annular groove in one of its sides to receive an annular flanged

projection, 4, on the standard B, which projection serves as a bearing for the pulley which receives in its groove the ring X, which is secured therein over the flange of the projection 4 by the screws 10, the ring to retain the pulley in place on the said standard. The pulley or disk C², as herein shown, has a grooved periphery to receive a belt from any suitable driving mechanism. The pulley C² has a central orifice, in which is placed the die-carrier C, provided with cutting-dies D, the die-carrier being open for the passage therethrough of the wire W to be threaded.

The thread-cutting dies D (shown separately in Fig. 5) are held in the die-carrier C by means of the plate o and screws r, and are made adjustable toward and from each other by the screws s, which act against the outer end of the dies. These dies nick or thread the wire as it is passed through between them. The forms of wire to be cut include all those shown in the patent referred to.

Some of the forms would require that one or both of the feed and press rolls be suitably grooved; but the flattened wire (shown in Fig. 3 of the drawings) is especially adapted for being fed and clamped by the cylindrical rolls shown, and it is the form that will be understood as being referred to in this description.

30 The feed rolls E are mounted upon shafts a b, having bearings one above the other in the arms of the standard L, and provided with intermeshing gears G to give motion in unison to the feed-rolls E. The lower shaft has a 35 worm-wheel, H, engaging the worm I on the shaft 5, bearing in the standard L and having a belt-pulley, J, to receive a belt from a suitable shaft to cause the feed-rolls to be speeded relatively with the die-pulley C². The upper 40 shaft, a, has its bearings in the movable arm K, fulcrumed at i and provided with a screw, k, passing down into the rigid arm to permit the upper feed-roll E to be adjusted with relation to the lower one, and thereby regulate 45 the pressure thereof on the wire passing between said feed-rolls.

The press-rolls F are mounted on shafts c d, the shaft c having bearings in the lower rigid arm of the standard N, and the shaft d being 50 secured in the movable arm M of the said standard, the said movable arm being fulcrumed at J and having a screw, l, to permit adjustment of the press-rolls F.

If desired, the press-rolls could also serve 55 as feed or driving rolls in connection with the rolls E by providing them with gearing similar to those provided for the rolls E, and further extending the shaft 5 and placing thereon a second worm, like the worm I. The 60 primary object, however, of the press-rolls F is to prevent the flattened wire (shown in Fig. 3) from being permanently twisted by the torsional strain due to the cutting action of the die D.

65 As the threads or nicks in the wire are required to be rather coarse, the rotating cutting action of the die tends all the more to

strain and give to the cut wire a permanent twist. With the feed-rolls E only, or with clamping mechanism in front of the pulley and die-carrier only, this torsional action of the die must be resisted by the torsional strength of the wire between the die and such feed-rolls or clamping means in front of the die; but by adding the press-rolls F to clamp 75 or hold the wire immediately in rear of the die, the torsional strength of the wire between the die and such press-rolls is added to resist the torsional action of the said die. This 80 double strength or increased resistance to the injurious action of the die is sufficient usually to prevent a serious permanent twist being imparted to the cut wire, while otherwise it is likely to leave the machine badly twisted.

But the press-rolls F have a further function. Should the die become so worn and dull as to seriously twist the wire on both sides of the die in spite of both feed and press rolls, it is to be observed that the wire between the said die and the press-rolls will be twisted in 90 a direction opposite to that between the die and feed-rolls. Then by a proper adjustment of the distance between the die and press-rolls the counter twist may be made just sufficient to straighten the direct twist, and thus enable 95 the wire to leave the machine true.

The press-rolls F are made large, so as to act better and afford more peripheral or engaging surfaces to engage the flat surfaces of the wire. A guide-piece, O², is secured to the 100 standard L in front of the feed-rolls, and is provided with a wire-receiving orifice arranged in the path of the wire through the machine to properly guide the wire to the feed-rolls.

I claim—

1. In a machine for nicking or threading wire, the combination, with a rotating die-carrier provided with nicking-die, of a pair of feed-rolls arranged in front of the die-carrier and a pair of press-rolls located in rear of the 110 said die-carrier, to operate substantially as described.

2. The combination, substantially as described, with a pair of feed-rolls, and a pair of press-rolls, of a pulley, C², provided with 115 a rotating die-carrier arranged intermediate of the feed and press rolls and having a die, D, the said pulley and die-carrier being made thin or constructed to occupy but little space in the direction of the path of the wire to 120 thereby permit the feed and press rolls to be placed in close proximity therewith, for the purpose specified.

3. The combination, with the standard provided with the flanged annulus, as described, 125 of the pulley C², having an annular groove in one of its sides and provided with a ring, X, substantially as and for the purpose set forth.

4. The combination, with a fixed standard provided with a pair of feed-rolls, and a standard made longitudinally movable and having a rotating die-carrier and a die, of a second movable standard adapted to have a longitudinal movement in rear of the said die-carrier,

and provided with a pair of press-rolls, substantially as and for the purpose specified.

5. In a machine for screw-threading wire, a standard having a rigid arm provided with a roll-shaft, combined with a movable arm having a rigid portion projecting at right angles thereto and fulcrumed to the said standard and provided with a roll-shaft, the said movable arm having an adjusting-screw pass-

ing down through it and entering the rigid arm of the standard, for the purpose set forth.

In testimony whereof I have signed my name to this specification in the presence of two subscribing witnesses.

STILLMAN W. ROBINSON.
